TOOTHPICK DISPENSER OR THE LIKE

William J. Meyer, Ridgewood, and Henry A. Flor,
Merrick, N. Y.

Application July 19, 1950, Serial No. 11,262

Term of patent 14 years

(Cl. D44—24)

To all whom it may concern:

Be it known that we, William J. Meyer, a citizen of the United States, residing at Ridgewood, county of Queens and State of New York, and Henry A. Flor, a citizen of the United States, residing at Merrick, county of Nassau and State of New York, have invented a new, original, and ornamental Design for a Toothpick Dispenser or the like, of which the following is a specification, reference being had to the accompanying drawing, forming a part hereof.

Fig. 1 is a side elevational view of a toothpick dispenser or the like showing our new design;

Fig. 2 is an end elevational view;

Fig. 3 is another side elevational view with the container portion in raised position;

Fig. 4 is an end elevational view corresponding to Fig. 3;

Fig. 5 is a top plan view; and

Fig. 6 is a vertical cross-sectional view thereof substantially through the center of the article.

We claim:

The ornamental design for a toothpick dispenser or the like, substantially as shown.

WILLIAM J. MEYER.
HENRY A. FLOR.
